UNITED STATES PATENT OFFICE.

ULYSSES F. HENDERSON, OF NEW LEBANON, PENNSYLVANIA.

DESIGN FOR A BICYCLE-HANDLE.

SPECIFICATION forming part of Design No. 26,542, dated January 19, 1897.

Application filed December 16, 1896. Serial No. 615,932. Term of patent 7 years.

To all whom it may concern:

Be it known that I, ULYSSES F. HENDERSON, a citizen of the United States, residing at New Lebanon, in the county of Mercer and State of Pennsylvania, have invented a new and original Design for a Handle for Bicycles, of which the following is a specification.

This invention relates to a new and original design for handle-bars for bicycles; and it has for its object to provide a design of this character that shall be both useful and ornamental.

The leading feature of the design resides in a handle-bar formed at each side of a central point between its ends with a complete circular convolution or coil whose center lies in a plane approximately parallel with a plane disposed longitudinally of the bar, thereby giving the convolution or coil a vertical disposition, the twist of the bar forming the convolution or coil thereof following a spiral line and thereby deflecting the terminals of the bar in an outward direction.

In the drawings, Figure 1 is a perspective view of a handle-bar embodying the herein-described design. Fig. 2 is a similar view showing the bar in a reversed position. Fig.

3 is a plan view of the bar. Fig. 4 is a sectional view on the line 4 4 of Fig. 3, looking toward one end of the bar.

Referring to the drawings, the numeral 1 designates a handle-bar provided with a central circular clip portion 2. At each side of the central circular clip portion 2 the bar is twisted to form a complete circular convolution or coil 3, whose center lies in a plane approximately parallel with a plane disposed longitudinally of the bar, thereby giving the convolution or coil a vertical disposition. The twist of the bar forming the convolution 40 or coil 3 follows a spiral line and causes the terminals 4 of the bar to be deflected in an outward direction.

What I claim is—

The design for a handle-bar for bicycles 45 herein shown and described.

In testimony that I claim the foregoing as my own I have hereto affixed my signature in the presence of two witnesses.

ULYSSES F. HENDERSON.

Witnesses:

A. BLATT,
C. F. WHEELER.
